(57) **CLAIM**

The ornamental design for a transferable hand grip device, as shown and described.

DESCRIPTION

FIG. 1 is a front right side perspective view showing the transferable hand grip device as my new design, wherein the front left side view is a mirror image thereof;
FIG. 2 is a front elevation view thereof,
FIG. 3 is a back elevation view thereof,
FIG. 4 is a left elevation view thereof,
FIG. 5 is a right elevation view thereof,
FIG. 6 is a top side elevation view thereof; and,
FIG. 7 is a bottom side elevation view thereof.
